Russell W. Everett,
ATTORNEY.

UNITED STATES PATENT OFFICE.

CHARLES BISHOP, OF NEWARK, NEW JERSEY.

LEATHER-STRETCHING FRAME.

1,199,756.

Specification of Letters Patent. Patented Oct. 3, 1916.

Application filed December 28, 1915. Serial No. 68,988.

To all whom it may concern:

Be it known that I, CHARLES BISHOP, a citizen of the United States, and a resident of Newark, in the county of Essex and State 5 of New Jersey, have invented certain new and useful Improvements in Leather-Stretching Frames, of which the following is a specification.

This invention relates more particularly 10 to that class of leather stretching frames used for stretching hides in the process of preparing the same for the market, the hide being stretched in its entirety without trimming off any of the irregularities and thus 15 requiring means for holding it to the frame which may be adjusted to fit any hide.

The objects of the invention are to provide such a frame adapted to secure and stretch hides varying in size and shape; to 20 avoid damaging the edges of the hide in securing it to the frame; to thus effect a saving in leather by not having to trim the same; to provide means for securing the hide to the frame which may be quickly applied or 25 moved; to provide such means which will grip the leather firmly and without puncturing or damaging the same; to obtain a thorough stretching of the hide; to apply a constant and even pull upon the hide for 30 stretching the same; to afford free access of air to both the outer and inner surfaces of the hide; to thus dry the hide without loss of time; to reduce expense of production of the leather; to secure simplicity of construction and operation, and to obtain other advantages and results as may be brought out 35 in the following description.

Referring to the accompanying drawings in which like numerals of reference indicate 40 the same parts throughout the several views; Figure 1 is a side elevation of a leather stretching frame embodying my invention; Fig. 2 is an end view of the same, and Figs. 45 3, 4 and 5 are cross-sections taken on lines A—A, B—B, and C—C respectively of Fig. 1.

In the specific embodiment of the invention illustrated in said drawings, the reference numeral 1 indicates a rail or pole supported in horizontal position in any suitable manner, as by resting at its ends upon beams 50 2, 2. Hanging over this rail 1 is a frame 3 comprising halves or sections 4, 4 one upon each side of the rail in substantial registration one with the other. Each of these sections comprises separated and substantially

parallel uprights 5, 6 at its opposite ends. Between the lower ends of these uprights is a bottom piece 7 fast with respect to the uprights and separating the same a sufficient 60 distance so that the hind shank and head or neck of a hide when stretched between said uprights will terminate thereupon. A corner filler 8 is provided between the bottom piece 7 and one of the uprights, as 6, this 65 corner piece being fast with respect to the said parts in the same plane therewith and of such proportions that the forepart or edge of the hide will overlie the same. 70

In operation, the hide is secured to the uprights, bottom piece and edge of the corner filler, it being understood that the hide is doubled upon itself through its middle and hung over the rail 1 so that its opposite sides may be clamped similarly upon the two sections. Obviously, therefore, half 75 of the hide will be upon one side of the frame and half upon the other, each half being securely clamped to the frame. Inasmuch as the frame 6 is vertically slidable upon the rail 1 its weight will be carried by the hide itself which is held up by the pole or rail 1. 80

As shown in the drawings, the sections 4, 85 4 of the frame are parallel and separated sufficiently to permit the rail to fit loosely therebetween, and at the upper ends, between the uprights 5, 6, spacing blocks 9, 9 are provided overlying the rail but sufficiently 90 separated therefrom so as not to interfere with the downward movement of the frame as the hide is stretched. Wedges or shims 10, 10 are provided which may be inserted between the blocks 9, 9 and the adjacent portions of the rail whereby the frame may be held at any desired height, such for instance, as when a hide is being clamped upon the frame, but it will be understood that these shims are removed after the hide is attached so as to allow the full weight of the frame to come upon and stretch the hide. 95 Adjacent the bottom of the frame the sections are held against separating, and I have shown braces 11, 11 at the ends of the sections for this purpose which may also be utilized as handles for grasping and raising the frame when so desired. 100

Preferably the clamps for securing the hide to the frame comprise cleats adapted to lie flatwise of the sections and bolted thereto. Beneath the cleats and between the bolts 105

are wedges which may be inserted laterally toward the edge of the hide to avoid wrinkling the same. In the present disclosure two such cleats are shown for the hind quarter of the hide upon the upright at the left hand end of Fig. 1, three cleats upon the bottom piece, one upon the corner filler, and a securing means for the head or neck of the hide upon the upright at the right hand end 10 of Fig. 1.

Referring to the clamps for the hind quarter of the hide at the left hand end of Fig. 1 upon the upright 5, both are substantially alike and extend longitudinally of 15 said upright at suitable distances apart. These clamps each comprise cleats 13 of sufficient length and strength for the purpose, the cleats having bolts 14, 14 adjacent their ends extending through the upright 20 and also through similar cleats 15 flat upon the back of the upright. The nut is preferably upon the outside of the section so that it may be readily tightened or loosened at will. A similar clamp is provided upon 25 the bottom piece 7 adjacent the end upright just described, this clamp being similar to those upon the upright and extending longitudinally of the bottom piece. It will be noted that these clamps so far described are 30 stationary, that is, do not move in the plane of the frame, and the hide in being secured to the frame is engaged first by these stationary clamps and then attached along the rest of its edges by movable clamps which 35 may be positioned wherever the hide requires the same.

A movable clamp is shown upon the bottom piece adjacent the end of the fixed clamp just described extending also longitudinally of the bottom piece and comprising a cleat 16 shown having bolts 17 securing it to the section and provided with wedges 18, 18 therebetween, in this instance a third bolt 17 being employed at the middle of the cleat between the ends of the two wedges. These bolts all pass through a cleat 19 upon the back of the bottom piece, and vertical slots 20 are provided in the bottom piece to allow the clamp to be raised 40 and lowered as may be necessary or desirable. It will be noted that by having the bolts extend through cleats upon both sides of the bottom piece the clamp is held together as a unit and may be moved to position with minimum effort and attention. As shown in the drawing, the slots 20 extend from about the middle of the bottom piece to its top, and a strip 21 along the top of said bottom piece closes the ends of the slots 45 so as to prevent the clamp from being removed and becoming lost or damaged as well as for reinforcing the bottom piece where weakened by cutting to make the slots. At the end of the clamp just described away from the fixed clamps or to-

ward the corner filler is a clamp 22 hinged upon the bottom piece and adapted to be positioned by swinging to whatever position it is required. This clamp comprises a cleat 23 bolted as at 24, said bolt forming a trunnion upon which the cleat may be swung. Adjacent its opposite end the cleat has another bolt 25 extending therethrough and through an arcuate slot 26 in the bottom piece and corner filler the center of curvature of which is at the trunnion bolt 24. In this way the cleat may be swung to whatever position it is needed. The cleat extends beyond the bolt 25 in the arcuate slot providing a suitable handle 27 by which the same may be manipulated. A wedge 28 is provided for this pivoted cleat adapted to be inserted thereunder and secure the hide in position.

Along the inner edge of the corner filler 55 is another clamp 29, providing a cleat 30 having bolts 31 at its opposite ends and one midway therebetween. These bolts extend through to the opposite side of the section and pass through a similar cleat 32. Slots 33 are provided for the bolts in the corner filler, of such shape as to permit the clamp to be either moved toward the edge of the corner filler or swung at an angle thereto. To effect this the opposite edges of the outside slots are substantially parallel to each other and perpendicular to the edge of the corner filler. These slots widen toward the edge of the filler, their edges which are nearest curving outward toward each other from 60 the small toward the large ends thereof. The middle slot has its edges curving outward toward the end slots so that its end toward the edge of the filler will be wider than its other end. Wedges 34, 34 are provided which can be inserted beneath the cleats and clamp the hide.

For purposes of illustration I have shown means of a different kind upon the upright adjacent the corner filler for securing the head or neck thereto, which comprises a plurality of vertical slots 33 arranged side by side and of sufficient length for the purpose. A wedge 36 substantially as long as the slots is provided which can be inserted 65 in any one of the same so as to stand perpendicular to the plane of the frame section. In securing the hide to the frame by this clamping means, the wedge is forced in one of the slots with the hide. It will be understood, however, that these various clamping means may be interchanged one for the other or all of one sort employed if so desired. It will be also noted, that the clamping means of each section are entirely independent of the clamping means of the other section so that the hide may be secured to first one side and then the other as may be desired.

The hides when applied to the frame are 130

usually wet and somewhat slippery, and in order to obtain a better clamp upon the same the sections are grooved longitudinally beneath the clamps as shown in the enlarged 5 section of Fig. 5 as at 37. By driving the wedges firmly between the cleats and the hide, the surface of the hide toward the frame and beneath the wedges will enter the grooves and thus form a very secure 10 attachment of the hide to the frame. Furthermore, a plurality of weights 38 are shown at the bottom of the frame which may be used or not as may be found desirable or necessary. These weights are shown 15 supported upon transverse pins 39 beneath the sections of the frame adjacent the bottom thereof.

In operation, the hide is drawn over the rail and with the shims inserted beneath 20 the spacing blocks to support the frame at the proper height the stationary clamps are first manipulated to secure the hind quarter of the hide to the frame, after which the movable clamps are positioned and their 25 wedges forced in to firmly grasp the hide. After the hide is thus attached to both sections of the frame, the shims are removed, which allows the weight of the frame to come upon the hide and stretch 30 the same. Weights may be applied in sufficient quantity to obtain the desired tension upon the hide, and it will be readily appreciated that the tension thus obtained is even and continuous so as to not strain the 35 leather suddenly or unduly. It may be pointed out, that a particular advantage of this frame resides in economy of space which is obtained by doubling the hide and at the same time obtaining a free passage 40 of air on both inside and outside of the hide. Also the entire value of the hide is retained, no holes or deformations spoiling any parts of it which will be readily recognized as advantageous and important. Furthermore 45 the time saved in applying a hide to the frame by my improved securing means is considerable.

Obviously detail modifications and changes may be made in manufacturing my 50 improved leather stretching frame without departing from the spirit and scope of the invention, and I do not wish to be understood as restricting myself except as required by the following claims when construed in the light of the prior art.

Having thus described the invention, what I claim is.

1. A leather stretching frame comprising a rail, sections slidable vertically at opposite sides of said rail adapted to receive 60 a hide hung upon said rail, and means for clamping said hide at its edges to the sec-

tions whereby the weight of the frame may be applied to the hide for stretching the same.

2. A leather stretching frame comprising a rail, separated sections slidable vertically at opposite sides of said rail adapted to receive a hide hung upon said rail and permit free access of air to the inner side thereof, and means for clamping said hide at its edges to the sections whereby the weight of the frame may be applied to the hide for stretching the same.

3. A leather stretching frame comprising a rail, sections slidable vertically at opposite sides of said rail adapted to receive a hide hung upon said rail, and a plurality of wedges coöperating with said sections for clamping said hide at its edges to the sections whereby the weight of the frame may be applied to the hide for stretching the same.

4. In a leather stretching frame adapted to receive and hold a hide extended, cleats 85 at intervals around the said frame, and wedges adapted to be inserted beneath said cleats for clamping the hide to the frame.

5. In a leather stretching frame adapted to receive and hold a hide extended, adjustable cleats at intervals around the said frame, and wedges adapted to be inserted beneath said cleats for clamping the hide to the frame.

6. In a leather stretching frame adapted to receive and hold a hide extended, a plurality of stationary cleats and a plurality of adjustable cleats arranged at intervals around the said frame, and wedges adapted to be inserted beneath said cleats for clamping the hide to the frame.

7. In a leather stretching frame adapted to receive and hold a hide extended, cleats at intervals around the frame, and wedges adapted to be inserted beneath said cleats 105 for clamping the hide to the frame, said frame providing grooves beneath a part of said wedges for obtaining a secure grip upon the hide.

8. In a leather stretching frame adapted to receive and hold a hide extended, said 110 frame providing a plurality of slots, a wedge adapted to be inserted in any one of said slots and carry a portion of the margin of the hide therewith for clamping the hide.

9. A leather stretching frame comprising a rail, sections slidable vertically at opposite sides of said rail adapted to receive a hide hung upon said rail, means for clamping said hide at its edges to the sections, 120 and weights upon the frame supported by the hide thereby stretching the same.

CHARLES BISHOP.
